UNITED STATES PATENT OFFICE.

JUSTUS A. TRAUT, OF NEW BRITAIN, CONNECTICUT.

SPIRIT-LEVEL.

SPECIFICATION forming part of Letters Patent No. 703,678, dated July 1, 1902.

Application filed January 28, 1902. Serial No. 91,547. (No model.)

To all whom it may concern:

Be it known that I, JUSTUS A. TRAUT, a citizen of the United States, residing in New Britain, in the county of Hartford and State of Connecticut, have invented certain new and useful Improvements in Spirit-Levels, of which the following is a specification.

This invention relates to spirit-levels; and it consists, substantially, in the improvements hereinafter more particularly described.

A great many disadvantages have been encountered hitherto in devices or implements of this kind, due largely to the insecure mounting of the level device (vial-glass case) proper upon the stock and also in some instances to the imperfect construction of the implement as a whole, rendering it frequently difficult to effect desired adjustments and often resulting in splitting of the stock and general dislocation or disorganization of the elements of the implement while in the hands of the mason or other operative. Other difficulties have also been encountered from a commercial point of view, due to the necessarily expensive character of the implement, rendered so from the unduly-complicated constructions resorted to in many instances.

The present invention has for its object to overcome the above-mentioned disadvantages and objections and to provide a device or implement of this kind in which either the level device (vial-glass case) proper or the stock therefor may be supplied to the trade separately or independently either for the purposes of repair or for replacing broken parts or for other purposes.

A further object is to so construct the implement as to obviate tendency to splitting of the stock thereof and to provide means whereby the vial-glass case or level device is not dislocated or affected on any variation of the pressure by which such device is clamped or fastened in place upon the stock.

A further object is to provide a seat for the level device of large capacity and also to so construct and organize the parts of the implement as to obviate any material reduction of the thickness of the stock at any point, thereby retaining maximum strength of the stock and materially adding to the general stability of the implement.

A still further object is to provide a con-

struction whereby the level device proper is centralized respecting both the width and thickness of the stock and also to provide means whereby most accurate adjustments of the said device may be made with ease and in the shortest space of time.

The above and additional objects are attained by means substantially such as are illustrated in the accompanying drawings, in which—

Figure 1 is a side view of a spirit or "mason's" level embodying my improvements, and Fig. 2 is a longitudinal sectional view thereof. Fig. 3 is an enlarged perspective view in detail, from which the general construction and organization of parts are more fully understood. Fig. 4 is an enlarged perspective view of the level device proper. Fig. 5 is a perspective view of the clamping-plate or washer, showing a preferred form. Fig. 6 is a perspective view similar to Fig. 4, showing a modification in the construction of the vial-glass case or level device proper. Fig. 7 is a side view in detail of a portion of the level, in which is embodied the case shown in the preceding figure; and Fig. 8 is a vertical sectional view thereof.

Before proceeding with a more detailed description it may be stated that in carrying my invention into effect I preferably give to the stock of the implement the general form used by bricklayers and masons—that is to say, I construct the same at or near each end with an opening for what may be termed the "plumb-glass," and intermediate such openings I provide a similar opening for the level-glass. I give to said stock, however, a special construction adjacent each of said openings, and I mount one of my improved level devices proper at each opening, although it will be understood that I may only employ a single device at any one of the openings, according to the particular use for which the implement is intended. My said improved level device proper is also of special construction and is adjustable on an invariable axis, and the same has a seat upon the stock in the direction of the greatest width thereof and is so organized that the clamping force or pressure is in a direction which in any variation thereof will not result in dislocation of the said level device, and in virtue of the con-

struction of the said device a seat of large capacity is obtained therefor. The level device proper is held in place or position upon the stock by means of a clamping plate and screw and is readily adjustable by means of a screw-driver or other implement on slightly loosening the screw.

Specific reference being had to the drawings by the designating characters thereon, A 10 represents the stock of my improved spirit-level, which, as will be observed, is preferably formed at each end with an opening *a* for the plumb-glass and the intermediate opening *b* for the leveling-glass, such being 15 the usual form of the well-known bricklayer's or mason's-level. Formed in the side of the stock at each of said openings is a recess *c*, which is substantially circular in form, except for the opening or break *d* in the wall 20 thereof, which break is located just at the base of the opening and is for the purpose hereinafter more clearly understood. Said recesses are of comparatively limited depth, by which to preserve as much as possible of 25 the material of the stock, and the bases and walls thereof constitute seats or bearings for the pendent or fastening portion of the level device A², presently to be described. The diameter of each of said recesses is also consider- 30 ably less than the distance between the lower curved portions of the sides of the adjacent opening in the stock which intersect the base of said opening, the purpose of this feature of construction being fully understood hereinafter. Formed in the stock centrally of each of said recesses is a hole 35 or opening *e* for the passage of the pin or screw *e'*, which constitutes a pivot or axis for said level device A², as well as a means of 40 tightening the same in place when combined with the washer or clamping-plate, also to be presently described. On the opposite side the stock is counterbored around each of said openings *e* for the reception of a nut *f*, by 45 which each of the level devices is secured in place. Referring now to the said level device (glass vial-case) proper A², it may be said that preferably I construct the same of sheet metal rolled up into the form of a tube 50 or vial-case B, leaving at one side a straight pendent shank or hanging portion *g*, the said portion being of substantially the same shape or contour as the recess *c* and fitting said recess preferably in the manner herein illus- 55 trated—that is to say, the width of said pendent portion *g* is considerably less than the distance between the ends of said tube or vial-case B, free access being thus afforded for the insertion of a suitable device or im- 60 plement beneath the end portions of said tube for purposes of adjustment of the leveling device. Said shank or hanging portion constitutes the means by which the said level device A² is mounted in position upon the stock, and 65 inasmuch as the same is pendent at the extreme side of the tubular portion B it follows that said tube is centralized between the sides

or walls of the said openings *a* and *b*. In this way the parts or elements are balanced and the vial-case or tube B brought to a position 70 by which it is protected from injury either from rough handling or from contact with external objects. The organization is such that the said case or tube extends nearly the full width of the opening in the stock, and 75 it is to be noted that the said shank or hanging portion is formed with a central hole or opening *g*², which coincides with the hole or opening *e* in the bottom of the recesses *c*, and through which opening the pin or screw *e'* 80 passes, as illustrated. The distance between the bottom or under side of the tube or case B and the base of the opening in the stock is comparatively limited, as will be seen, so that no considerable displacement of the 85 leveling device on its axis is possible at any time. The relation between the tube B and hanging portion *g* is also such that but a comparatively small part of the material of the stock is required to be removed, thus retaining 90 maximum strength of stock, and it is explained that the function of the break *d* in the wall of each of the recesses is to enable the proper fitting of the pendent portion *g* in the recess, as well as the clamping-plate or 95 washer therefor hereinafter referred to, it being evident that such fitting of such elements or parts of the device could not be effected if the wall of the recess was closed or continuous at such point. The said break 100 therefore is an important feature of the construction, as will appear. The said hanging portion or shank may be extended for a considerable distance from the tube, thus obtaining a very large seat or mounting for the 105 level device upon the stock.

At each of the openings in the stock the shank or hanging portion *g* of the level device proper lies flatly against the base of the recess *c*, the edge of said hanging portion 110 working upon or against the inner surface of the side or wall of such recess, and fitting within such recess and lying against the shank or hanging portion is a clamping-plate or washer C, which is preferably hollowed out 115 or flanged for the purposes of lightness and which also has a central opening *m*, coinciding with the openings *e* and *g*², and through which the clamping-screw *e'* also passes. The said plate is preferably constructed to completely fill the remainder of the recess, so as 120 to be flush with the surface of the stock, and thus closing a space which would otherwise tend to collect mortar and other foreign substances. This construction also furnishes a 125 bearing for the enlarged end of the screw *e'*, serving to prevent flexure of the same in the event of any stress being brought to bear thereon from above, and the clamping-pressure is distributed by said plate or washer over a 130 large area, thereby serving to hold the level device proper in position with great security.

In order to protect the vial-glass in the end openings of the stock from injury or break-

age from the plumb-bobs usually employed with this class of levels, I prefer to employ some form of guard or protector therefor, and while various forms thereof may be adopted 5 I construct the same in some instances as an integral part of the clamping-plate or washer C, and the preferred form of which is indicated in Fig. 5. In said figure a sort of frame is cast or formed with said plate or washer, 10 constituted of two upright portions $n' n'$, connected by cross pieces or rods $n^2 n^2$, and said upright portions are bent so as to cause the rods to lie over or above the vial-glass, as indicated in Fig. 3, for instance. The dotted 15 lines in Fig. 5 show the straight form of the frame previous to the bending over of the uprights $n' n'$. These latter, it may be remarked, are usually located about at the ends of the vial-glass, and, taking the structure as 20 a whole, it will be seen that a simple and most effective guard is secured. It is of course evident that I am not limited to this precise form, nor is it to be understood that the clamping-plate or washer necessarily involves 25 as a component thereof any such guard structure, for it is evident that the function of each of these said elements is entirely separate and apart from each other. The construction has been found practical and con- 30 venient, and for which reason it is preferred. Fig. 3 indicates very clearly the construction and organization of my improved spirit-level, and on reference thereto it will be seen how the adjustment of the level device proper may 35 be effected by the simple introduction of a screw-driver or other implement (operating as a wedge or a lever) after the screw e' has been slightly loosened. By loosening said screw the pressure of the clamp-plate or washer C 40 against the shank or pendent portion of the level device A^2 is of course relieved, and then the said device may be turned up or adjusted from either end, as is evident.

My improved level has the advantage that 45 the level device is adjustable on a fixed center or upon an axis having no variation or shifting from an established point or position, and it will be seen that from such an organization the most accurate and reliable adjust- 50 ments may be effected by simply turning the level device in one direction or the other. After adjustments are effected the clamp-plate or washer is of course again tightened, the pressure exerted thereby covering a large 55 area and establishing a firm and extended bearing for the level device A^2 . It will be understood that in making adjustments the pressure is never entirely removed from the clamp-plate, but only reduced, so that alignment 60 is preserved. From the construction such as I have illustrated it will be seen that at the point of mounting of the level device upon the stock portions of the latter are securely clamped by the several elements— 65 that is to say, between the hanging portion g and the fastening-nut f —and in this way tend-

ency to splitting of the stock is largely overcome.

The use herein of the terms "pendent" portion and "hanging" portion will of course 70 be understood as being intended to apply to the structure when the leveling devices proper are in a horizontal position, or approximately so.

In Figs. 6, 7, and 8 I have shown a modification of my invention wherein I form or construct the pendent or hanging portion g with oppositely-disposed concentric arc-slots $g^6 g^6$, and inserted in the wood of the stock through said slots are screws $g^7 g^7$, which are so adjusted 75 that the heads thereof bear with sufficient friction to prevent the level device A^2 from falling out of alignment at times when the clamp-plate is loosened up for adjustments. Said screws frictionally hold the level device 80 proper to whatever position it may be turned or adjusted, but do not exert pressure enough to require to be loosened when new adjustments are to be made. This construction is effective, but is not intended to supersede 85 the structure first described.

From the foregoing it will be seen that I have provided a level-stock and level device proper each especially adapted to the other, and it will also be seen that they may be 90 supplied to the trade either separately or combined. If in the use of the implement either one or the other of said elements should become impaired or be rendered useless from any cause, it may easily be replaced, 95 while the element remaining is still available for use therewith.

I have herein emphasized several important features of my invention and in doing so have of course referred to the annexed 100 drawings, wherein a selected embodiment is shown. It will be understood, however, that I do not limit myself in practice to any of the precise details of construction and organization of such embodiment, since various 105 changes therein may be made and still come within the spirit and scope of my invention.

Having described my invention, I claim—

1. A spirit-level comprising a stock having an opening therethrough and formed in one 110 side with a recess having a break in the wall thereof at the base of such opening, a vial-tube located within the sides of the opening parallel with said base and having a pendent portion extending through said break and seated in said recess, and means for clamping 115 said pendent portion to the base of the recess, said means including a guard extending over said vial-tube.

2. A spirit-level comprising a stock having an opening therethrough and formed in one 120 side with a recess having a break in the wall thereof at the base of such opening, a vial-tube located within the sides of the opening parallel with said base and having a pendent 125 portion extending through said break and adjustable in the recess on an invariable axis,

and means for clamping said pendent portion to the base of said recess, said means including a guard extending over said vial-tube.

3. A spirit-level comprising a stock having an opening therethrough and formed in one side with an approximately circular recess having a break in the wall thereof at the base of such opening, a vial-tube located within the sides of the opening parallel with said base 10 and having a pendent portion approximating the greater part of a circle in shape extending through said break and adjustable in the recess on an invariable axis, and means for clamping said pendent portion in place, said 15 means including a guard extending over said vial-tube.

4. A spirit-level comprising a stock having an opening therethrough and formed in one side with an approximately circular recess 20 having a break in the wall thereof at the base of such opening, a vial-tube located within the sides of the opening parallel with the base thereof and having a pendent portion approximating the greater part of a circle in shape 25 extending through said break and adjustable in the recess on an invariable axis, and a clamping device for said pendent portion having the same axis, said device including a guard extending over said vial-tube.

5. A spirit-level comprising a stock having an opening therethrough and formed in one side with an approximately circular recess having a break in the wall thereof at the base of such opening, a vial-tube located within 35 the sides of the opening parallel with the base thereof and having a pendent portion approximating the greater part of a circle in shape extending through said break and adjustable in the recess on an invariable axis, a plate or 40 washer also seated in the recess flush with the surface of the stock, and means for clamping said plate or washer against the pendent portion to hold the leveling device in place, said plate or washer being provided with a 45 guard extending over said vial-tube.

6. A spirit-level comprising a stock having an opening therethrough and formed in one side with an approximately circular recess having a break in the wall thereof at the base 50 of such opening, a vial-tube located within the sides of the opening parallel with the base thereof and having a pendent portion approximating the greater part of a circle in shape extending through said break and adjustable 55 in the recess on an invariable axis, a removable axial member on which the pendent portion is adjustable, and means clamping said pendent portion in place, said means including a guard extending over said vial-tube.

7. A spirit-level comprising a stock having an opening therethrough and formed in one side with an approximately circular recess having a break in the wall thereof at the base 60 of such opening, a vial-tube located within the sides of the opening parallel with said base and having a pendent portion approximating

the greater part of a circle in shape extending through said break and seated in the recess, and a clamping device for said pendent portion including a washer, a screw, and a 70 nut, said washer being provided with a guard extending over said vial-tube.

8. A spirit-level comprising a stock having an opening therethrough and formed in one side with an approximately circular recess 75 having a break in the wall thereof at the base of such opening, a vial-tube located within the sides of the opening parallel with said base and having a pendent portion approximating the greater part of a circle in shape extending through said break and seated in the recess, said pendent portion having a central 80 opening registering with a corresponding opening formed in the stock centrally of the recess, an axial member for the support of 85 the pendent portion, and a plate and a nut on such member at opposite sides of the stock for securing said pendent portion in position, said plate being provided with a guard extending over said vial-tube.

9. A spirit-level comprising a stock having an opening therethrough and formed in one side with an approximately circular recess less 90 in diameter than the distance between adjacent parts of the sides of said opening, and having a break in the wall thereof at the base of the opening, a vial-tube located within the sides of said opening parallel with said base and having a pendent portion approximating the greater part of a circle in shape extending 95 through said break and adjustably secured in the recess, the ends of said tube projecting beyond the edges of said pendent portion, and means for securing said pendent portion in place including a guard extending 100 over the vial-tube.

10. A spirit-level comprising a stock, a leveling device, and a clamp for the leveling device including a washer and a guard integral therewith, said guard being formed of an upright frame and connecting-bars, and said frame being bent to bring the bars directly 110 above said leveling device.

11. A spirit-level comprising a stock having an opening therethrough and formed in one side with an approximately circular recess 115 having a break in the wall thereof at the base of such opening, a vial-tube located within the sides of the opening parallel with the base thereof and having a pendent portion approximating the greater part of a circle in shape 120 passing through said break and seated in the recess, said pendent portion being adjustable on an invariable axis and formed with concentric arc-slots on opposite sides of 125 said axis, screws entering the base of the recess through said slots, and a washer, a screw, and a nut for clamping said pendent portion in place.

12. A spirit-level comprising a stock having 130 an opening therethrough and formed in one side with an approximately circular recess

- having a break in the wall thereof at the base of such opening, a vial-tube located within the sides of the opening parallel with said base and having a pendent portion approximating the greater part of a circle in shape extending through said break and seated in the recess, and a clamp for said pendent portion including a washer having a guard integral therewith formed of an upright frame and connecting-bars, said frame being bent to bring the bars directly above said vial-tube. 5
13. A spirit-level comprising a stock having an opening therethrough and formed in one side with an approximately circular recess having a break in the wall thereof at the base of such opening, a vial-tube located within the sides of the opening parallel with the base thereof and having a pendent portion approximating the greater part of a circle in shape passing through said break and seated 15 in the recess, said pendent portion being adjustable on an invariable axis and formed with concentric arc-slots on opposite sides of said axis, screws entering the base of the recess through said slots, and a washer, a screw, 20 and a nut, for clamping said pendent portion in place, said washer being provided with a guard extending over the said vial-tube. 25
14. A spirit-level comprising a stock having an opening therethrough and formed in one side with an approximately circular recess having a break in the wall thereof at the base of such opening, a vial-tube located within the sides of the opening parallel with the base thereof and having a pendent portion approximating the greater part of a circle in shape passing through said break and seated 30 seated in the recess, said pendent portion being adjustable on an invariable axis and formed with concentric arc-slots on opposite sides of said axis, screws entering the base of the recess through said slots, and a washer, a screw, 35 and a nut, for clamping said pendent portion in place, said washer being provided with a guard extending over the said vial-tube. 40
